CLAIM

The ornamental design for a mattress, as shown and described.

DESCRIPTION

FIG. 1 is a perspective view of a first embodiment of a mattress;

FIG. 2 is a plan view thereof;

FIG. 3 is a first side view thereof, the opposed side view being the same;

FIG. 4 is a front view thereof, the rear view being the same;

FIG. 5 is a perspective view of a second embodiment of a mattress;

FIG. 6 is a plan view thereof;

FIG. 7 is a first side view thereof, the opposed side view being the same; and,

FIG. 8 is a front view thereof, the rear view being the same. The grayscale shading of the elements (white, grey and black) is intended to better illustrate the contour of the mattress and no surface ornamentation is hereby claimed.

(Continued)

The Mattress is shown with a symbolic break in its width.
The appearance of any portion of the article between the
break lines forms no part of the claimed design.
